Primary Examiner — Mark Goodwin(74) *Attorney, Agent, or Firm* — Finnegan, Henderson, Farabow, Garrett & Dunner, LLP(57) **CLAIM**

The ornamental design for a meter instrument panel, as shown and described.

DESCRIPTION

FIG. 1 is a front elevation view of a meter instrument panel showing our new design;

FIG. 2 is a left side view thereof;

FIG. 3 is a right side view thereof;

FIG. 4 is the rear elevation view thereof;

FIG. 5 is a top plan view thereof;

FIG. 6 is a bottom view thereof; and,

FIG. 7 is a cross-section view of the panel taken along the line 7-7 shown in FIG. 1.

The broken lines of uneven length set out the outer boundary of our design. The broken lines of even length shown in the drawings illustrate portions of the meter instrument panel that form no part of the claimed design.
